CLAIM

The ornamental design for a twisted whiskey glass with a cigar rest, as shown and described.

DESCRIPTION

FIG. 1 is an environmental perspective view of a twisted whiskey glass with a cigar rest showing my new design;

FIG. 2 is an alternate perspective view thereof;

FIG. 3 is a rear elevational view thereof;

FIG. 4 is a rear elevational view thereof;

FIG. 5 is a left-side elevational view thereof;

FIG. 6 is a rear elevational view thereof;

FIG. 7 is a top plan view thereof; and,

FIG. 8 is a bottom plan view thereof.

The broken lines showing a drink, ice, and a cigar in FIG. 1 depict environmental matter and form no part of the claimed design.

1 Claim, 8 Drawing Sheets
